UNITED STATES PATENT OFFICE

2,513,135

KEY HOLDER

Raleigh T. Barber, Tampa, Fla.

Application October 14, 1947, Serial No. 779,773

7 Claims. (Cl. 150—40)

1

This invention relates to key holders of the type wherein a plurality of keys are adapted to be pivotally mounted and held therein by a closure flap, and from which a selected key may be extended for use after the flap has been opened. When a number of keys are contained within a holder, it is frequently difficult to readily select the needed key from the lot, especially in the dark. This is particularly true in regard to automobile keys, when the door key, or the ignition key must be selected without the aid of adequate light.

The object of the present invention is to provide a key holder equipped with means for projecting a desired key upon opening the closure flap.

A further object of the invention is to provide a device as mentioned in which the projecting means may be selectively engaged with any one of the keys.

Further objects of the invention are, to provide a device as mentioned which shall be simple of construction, easy to operate, and of low cost to manufacture.

A still further object is to provide a device of the character above stated wherein the projector element may be replaced with facility when necessary, and at negligible cost.

Other objects will appear hereinafter.

With these objects in view, the invention consists generally in a body portion including a pair of substantially parallel walls, means for pivotally mounting a plurality of keys therein, a closure flap normally holding the keys within said body, and an elastic loop adapted to be selectively engaged with one of the keys, and adapted to project the selected key when the flap is opened.

The invention further consists in various details of construction and arrangements of parts, all as will be fully described hereinafter and particularly pointed out in the claims.

The invention will be more readily understood by reference to the accompanying drawings, forming a part of this specification and in which:

Figure 1 is a perspective view of a key holder embodying the invention,

Figure 2 is a side elevation of the same, illustrated in open position, and with a portion of the near side wall broken away,

Figure 3 is an edge view of one end of the device, upon an enlarged scale, and the several elements spread laterally to better illustrate the construction,

Figure 4 is a section taken on the line 4—4 of Figure 3,

Figure 5 is a detail perspective view of the elastic element preferably used in the device, illustrating the same in the form or shape it takes when in position therein,

2

Figure 6 is a detail sectional view taken on the line 6—6 of Figure 4, with the elements laterally spaced for clearness of illustration.

Figure 7 is a side elevation of a key holder provided with a modified form of ejecting means.

Figure 8 is a section on the line 8—8 of Figure 7, upon an enlarged scale.

Figure 9 is a detail view of one end of a key holder equipped with a further modification of the invention.

Figure 10 is a section on the line 10—10 of Figure 9.

Figure 11 is a view similar to Figure 9 but illustrating a further modification, and

Figure 12 is a section on the line 12—12 of Figure 11.

Referring to the drawings, 10 indicates the body of the key holder, which may be, but not necessarily, formed of a pliable material such as leather or the like; and includes a pair of normally substantially parallel side walls 11 and 12. The walls 11 and 12 are preferably narrow and elongated, and terminate in rounded end portions 13—13 and 14—14, respectively. The walls, intermediate said rounded ends, are connected by a back portion 15 which, if the device is flexible, may serve as a hinge connection between the walls.

The keys are pivotally mounted between the walls 11 and 12 as will be described hereinafter; and a closure flap 16 extends from the front edge of the wall 11 across the corresponding edge of the wall 12 to retain the keys within the holder. When the device is closed, the flap 16 is secured in any desired manner, as by a snap fastener 17.

The holder may be designed to pivotally support the keys in one end only of the body 10; but preferably the ends are similar as illustrated, so as to accommodate a larger number of keys; also for a further purpose as will appear hereinafter. However, as both ends are identical in construction, the description of one will suffice for both.

Adjacent each end, the walls 11 and 12 are provided with eyelets 18 and 19, respectively through which are extended the element upon which the keys 20 are pivotally mounted. As illustrated in the drawings, this element comprises an endless elastic tension band 21 which may be of rubber or other elastic material, and may be either covered or uncovered as preferred.

To place the keys 20 in the holder, the band 21 is laterally contracted with the laps 22 thereof in close proximity, and terminating in end loops 23 and 24 respectively, and the looped end 23 is threaded through the usual holes 25 in the keys 20, then outwardly through the eyelet 19, and then over the outer edge of the end 14 and spanning the keys. The free end loop 24 is then threaded through the loop 23, passed

through the eyelet 18 in the wall 11, then over the outer edge of the end 13, and looped over the selected key, as shown in Figures 2, 3, 4 and 6 of the drawings. The keys are then positioned within the holder and the flap 16 secured by the snap fastener 17.

When the flap 16 is opened the selected key to which the loop 24 has been engaged will be raised or projected above the other adjacent keys so that it may be readily identified even in the dark, thereby eliminating the necessity of trying several keys in order to find the right one.

In using the device, the loop 24 is engaged over the key which is expected to be next used; and it is obvious that for this purpose the loop 24 may be readily shifted from one key to another. Sometimes it is desirable to have two keys that are to be used in succession, projected or raised from the other keys, such as the car door key and the ignition key, or the ignition and radio keys, or any other useful or needed combination. For this purpose the double ended holder as illustrated in the drawings may be found of great service.

In Figures 7 and 8 a modified form of the invention is illustrated, wherein the elastic tension member 21¹ is secured at one looped end 23¹ thereof to a shank 27 of a button 28, said shank extending through the eyelet 18 in the end 13. The member 21¹ is threaded through the holes in the keys and the eyelet 19 and then extended over the edge of the end 14 and looped over the selected key.

A further modification is illustrated in Figures 9 and 10. In this form of the device the key holder is provided with the usual separable pivot members 29 having the heads 30. An endless elastic tension member 21² is looped over one end of the pivot member 29 between one end 13 or 14 of the holder and the adjacent head 30 of said pivot member, and then passed over the edge of the end of the holder and looped about the selected key.

Another modification is illustrated in Figures 11 and 12, wherein one end of a looped elastic member 21³ is secured to the inner face of an end 13 or 14 of the holder as by a rivet 33 or other similar device and the other end of said member is looped over the selected key. The securing member 33 is arranged adjacent the periphery of the end to which it is secured, and above the median line 34 of the holder extending between the key supporting members 29 so that when the selected key is depressed within the holder to be held by the flap 16, considerable tension is exerted on the key by the member 21³.

I claim:

1. In a key holder for a plurality of keys having a common pivotal axis, an elastic loop attached to said holder and adapted to be engaged under tension around the shank portion of a selected key.

2. In a key holder, a body including a pair of substantially parallel walls, means for pivotally mounting a plurality of keys between said walls on a common axis, a releasable retaining means for said keys, and an elastic loop tension member adapted to be selectively engaged with one of said keys and adapted to project the selected key beyond the remaining keys when said retaining means is released.

3. In a key holder a body including a pair of substantially parallel walls, means for pivotally

mounting a plurality of keys between said walls on a common axis, a releasable retaining means for said keys, and an elastic tension member comprising a loop extending from the outside of said body over the edge of one of said walls to be selectively engaged over one of said keys and adapted to project the selected key beyond the remaining keys when said retaining means is released.

4. In a key holder, a body including a pair of substantially parallel walls provided with aligned eyelets, and a combined pivotal means for a plurality of keys and selective ejector of one of the keys, comprising an endless elastic tension member threadable through said eyelets and the holes in the heads of the keys, one end of said tension member forming a loop extending over the end of one of said walls and about the portion extending between the eyelets, and the other end forming a loop adapted to be extended over the edge of the other wall and to be selectively engaged over one of the keys and a flap on one of said side walls and releasably attached to the other wall for normally retaining the keys in the body.

5. In a key holder an elongated body open at one side, and adapted to contain a plurality of keys at each end of said body for pivotally mounting a group of keys adjacent said ends, and each of said means terminating in a flexible tension loop to be selectively engaged over one key of the respective group, and a releasable single flap on said body adapted to span the open side thereof to retain the keys of both groups within the body.

6. In a key holder a body including a pair of parallel walls, a separable pivot pin for a plurality of keys and having retaining heads on the outer ends thereof, and a retaining flap for said keys, in combination with a looped elastic tension member having one end thereof looped over said pin between one of said walls and the adjacent retaining head, and adapted to be extended over the end of said wall and looped over one of the keys.

7. In a key holder a body comprising a pair of substantially parallel walls, a separable pivot pin for a plurality of keys and having retaining heads on the outer ends thereof, and a retaining flap for said keys, in combination with a looped elastic tension member, means for securing said tension member to the inner face of one of said walls at a point outwardly of the axis of said pivot pin and between the median line of the holder passing through said pin and the line of the inner edge of the flap, the other end of said tension member being adapted to be looped over one of the keys on said pivot pin.

RALEIGH T. BARBER.
